FEED FINGER FOR CIRCULAR KNITTING MACHINES

Frederick Scarborough, Northampton, Mass.

Application December 14, 1953, Serial No. 398,097

8 Claims. (Cl. 66—125)

This invention relates to knitting machines of the circular type, such as are used for knitting hosiery, underwear, sweaters and neckties. More particularly, the invention has reference to a feed finger for such a machine, said finger carrying a projecting pin known as a "tube" through which the yarn extends.

Normally, a feed finger is a one-piece casting. As a result, when a pin or tube breaks, the entire finger must be replaced.

An important object of the present invention, therefore, is to provide a feed finger having a tube-holding slide which can be removed from the body of the finger when a tube breaks, thus eliminating the necessity of replacing the entire finger.

A further object is to provide a device as stated wherein the removable and replaceable slide can be adjusted any desired distance from the needle of the knitting machine. In this way, it is proposed to eliminate the presently existing requirement of stocking fingers in a number of different sizes.

Yet another object is to provide a novelly designed tube that will be particularly well adapted for mounting in a slide of the nature referred to above.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

Fig. 1 is a side elevational view of the feed finger, the dotted lines showing one adjusted position.

Fig. 2 is an edge view of the finger seen from the right of Fig. 1.

Fig. 3 is a top plan view.

Fig. 4 is a fragmentary side elevational view showing the side opposite that seen in Fig. 1.

Fig. 5 is a sectional view on line 5—5 of Fig. 1.

Fig. 6 is an enlarged sectional view on line 6—6 of Fig. 1.

Fig. 7 is a greatly enlarged sectional view on line 7—7 of Fig. 1.

Fig. 8 is a still further enlarged elevational view of the tube.

Fig. 9 is a sectional view on line 9—9 of Fig. 8.

The feed finger 10 includes a casting formed with a flat, elongated, arcuately bowed arm 12 integral at its upper end with a widened head 14 having a mounting member-receiving opening 16. At its lower end arm 12 is integral with a horizontally extended, flat guide portion 18 disposed in a vertical plane and having one of its side surfaces formed with a horizontally extending guideway 20.

The guideway 20 is formed as a shallow groove open at its opposite ends, and provided with straight, parallel side walls. Slidably adjustable in the groove is a flat, relatively thin slide 22, the inner end of which has integral flanges 24 on its opposite longitudinal edges. The flanges both extend in the same direction out of the main plane of the slide (Fig. 6) and provide thickened bearing surfaces snugly and slidably fitted against the respective side walls of the groove.

A longitudinally and centrally disposed, closed slot 26 is formed in the slide between the guide flanges 24, and receives the shank of a set screw 28 threaded in an opening 29 of the portion 18. Thus, the slide can be adjusted

2

to any of several positions, two of which are shown in full and dotted lines in Figs. 1 and 3. In each position the set screw is tightened to hold the slide in the selected adjustment.

5 This eliminates the necessity of maintaining a plurality of fingers in different sizes, and further, the breaking of a tube does not require removal of the entire finger, since only the slide need be removed.

The outer end of the slide is formed integrally with a head 30 having in its upper surface a straight-sided groove 32. A tube 34 is engaged in a vertical bore 36 opening at its upper end into the groove and opening onto the underside of the head at its lower end. The tube, at its upper end, is formed with a square head 38 that defines at its lower end a downwardly facing shoulder 40 engageable against the base of groove 32 to limit downward movement of the tube in bore 36. The sides 42 of the head 38, meanwhile, engage the sides of the groove, to hold the tube against rotation.

20 At its lower end the tube is beveled as at 44.

The particular formation of the tube serves, of course, to effect a proper setting of the tube in head 30 with a minimum of difficulty. Merely by bringing the sides 42 into alignment with the sides of groove 32, the beveled end will be properly located.

25 The shoulder 40, at the same time, serves to hold the tube against downward movement, thus cooperating with the sides 42 in properly positioning the tube.

While I have illustrated and described the preferred embodiment of my invention, it is to be understood that I do not limit myself to the precise construction herein disclosed, and the right is reserved to all changes and modifications coming within the scope of the invention as defined in the appended claims.

30 Having thus described my invention, what I claim as new, and desire to secure by United States Letters Patent is:

1. A feed finger for circular knitting machines comprising an arm, and a slide adjustably connected thereto and adapted for holding a yarn carrier tube, said finger including a guide portion rigid with one end of the arm and having a guideway in which the slide is slidably fitted, the slide having a longitudinal slot, said finger including a set screw extending through said slot and threadably engaged in the guide portion to retain the slide in selected positions of adjustment.

2. A feed finger for circular knitting machines comprising a casting including an arm, means at one end of the arm to mount the same on a knitting machine, and a guide portion on the other end of the arm, said guide portion having a recess formed in one side thereof, a slide engaged in said recess, said slide including guide flanges at one end slidably engaged with the walls of the slot, and a head at its other end formed with a tube-receiving bore, the slide having a slot, and a set screw threaded in the guide portion and extending through said slot to hold the slide in selected positions of adjustment.

3. A feed finger for circular knitting machines comprising a casting including an arm, means at one end of the arm to mount the same on a knitting machine, and a guide portion on the other end of the arm, said guide portion having a recess formed in one side thereof, a slide engaged in said recess, said slide including guide flanges at one end slidably engaged with the walls of the slot, and a head at its other end formed with a tube-receiving bore, the slide having a slot, and a set screw threaded in the guide portion and extending through said slot to hold the slide in selected positions of adjustment, the slide being formed as a flat member and the guide flanges projecting in one direction out of the main plane of said member.

4. A feed finger for circular knitting machines comprising a casting including an arm, means at one end of the arm to mount the same on a knitting machine, and a guide portion on the other end of the arm, said guide portion having a recess formed in one side thereof, a slide engaged in said recess, said slide including guide flanges at one end slidably engaged with the walls of the slot, and a head at its other end formed with a tube-receiving bore, the slide having a slot, and a set screw

threaded in the guide portion and extending through said slot to hold the slide in selected positions of adjustment, the slide being formed as a flat member and the guide flanges projecting in one direction out of the main plane of said member, the head of said slide having a recess communicating with the bore and adapted to receive the head of a supported tube.

5. A feed finger for circular knitting machines comprising a casting including an arm, means at one end of the arm to mount the same on a knitting machine, and a guide portion on the other end of the arm, said guide portion having a recess formed in one side thereof, a slide engaged in said recess, said slide including guide flanges at one end slidably engaged with the walls of the slot, and a head at its other end formed with a tube-receiving bore, the slide having a slot, and a set screw threaded in the guide portion and extending through said slot to hold the slide in selected positions of adjustment, the slide being formed as a flat member and the guide flanges projecting in one direction out of the main plane of said member, the head of said slide having a recess communicating with the bore and adapted to receive the head of a supported tube, said recess of the slide head having straight, flat side walls for engagement of complementary side surfaces of a tube head, thus to hold the supported tube against rotation.

6. A feed finger for circular knitting machines comprising a casting including an arm, means at one end of the arm to mount the same on a knitting machine, and a guide portion on the other end of the arm, said guide portion having a recess formed in one side thereof, a slide engaged in said recess, said slide including guide flanges at one end slidably engaged with the walls of the slot, and a head at its other end formed with a tube-receiving bore, the slide having a slot, and a set screw threaded in the guide portion and extending through said

slot to hold the slide in selected positions of adjustment, the slide being formed as a flat member and the guide flanges projecting in one direction out of the main plane of said member, the head of said slide having a recess communicating with the bore and adapted to receive the head of a supported tube, said recess of the slide head having straight, flat side walls for engagement of complementary side surfaces of a tube head, thus to hold the supported tube against rotation, the slide head recess having in addition a flat bottom surface adapted to engage a shoulder on the supported tube to limit endwise movement of the tube in one direction.

7. A yarn carrier tube for circular knitting machines comprising a tubular body, and an enlarged head on one end of the body, said head being of cubical configuration.

15 8. A yarn carrier tube for circular knitting machines comprising a tubular body, and an enlarged head on one end of the body, said head being of cubical configuration, the head being substantially greater in respect to its transverse dimension than the diameter of the tube, thus to form a shoulder at the base of the head.
